SLIDING JAW WRENCH WITH OPPOSITELY THREADED SCREW ADJUSTMENT

Thomas L. Mayrath, Dodge City, Kans.

Application May 15, 1946, Serial No. 669,773

3 Claims. (Cl. 81—163)

(Granted under the act of March 3, 1883, as amended April 30, 1928; 370 O. G. 757)

1

The invention described herein may be manufactured and used by or for the Government for governmental purposes without payment to me of any royalty thereon.

This invention relates to an adjustable wrench which is especially useful for aircraft servicing, but is also capable of general use.

One object of the invention is to provide a wrench which is overall relatively thin in comparison to the thickness of the jaws, the width of the jaw opening and the strength of the wrench.

Another object is to provide a wrench, the parts of which can be readily fabricated from steel plate and bar stock without the using of forging dies.

Another object is to provide a screw adjustment which is readily accessible to the operator, even when he is wearing gloves. The adjusting screw is subjected only to tension when the wrench is used; therefore it is not likely to be bent or otherwise deformed during use of the wrench. Even though the jaws have taken a permanent deformation from an overload, the screw is still easy to adjust.

In the drawings,

Fig. 1 is a side elevation of the complete assembly.

Fig. 2 is a sectional view of the wrench with the adjustable jaw removed, taken on the line 2—2 of Fig. 1.

Fig. 3 is a front view of the adjustable jaw taken on the line 3—3 of Fig. 1.

10 is a single unit comprising a fixed jaw 11 a flat shank 12 and a handle 13. Connecting the shank and the jaw, there is an incline 14 which is preferably of 30° but which may be somewhat steeper or less steep. Slidably fitted on the shank 12, there is an adjustable jaw 15 which is provided with a loosely fitted, integral collar portion 16, which encircles and is slidable upon shank 12 up to the point at which incline 14 begins. There is also a forwardly pointed triangular projection 17 integral with jaw 15, the lower surface of said projection being slanted at the same angle as incline 14. A polygonal opening is thereby formed between the jaws which is well adapted at its lower corner, to accommodate the angle of a hexagon nut.

As will be seen by inspection of the figures, there is an inclined slot 19 extending preferably, but not necessarily entirely thru shank 12 and the shoulder 18 where that shank joins jaw 10. The slot 19 is preferably oblong, as shown, but may be of any suitable shape. It is provided to

accommodate an adjusting screw 20. A second slot 19a extends thru the movable jaw as shown and is similar to and registerable with the first. The screw 20 comprises a stem 21 which has two threaded portions 22 and 23, the threads of which are opposed. The stem extends thru both slots 19 and 19a. The threading is such that when the screw is rotated in its supports, i. e. trunnion nuts 24 and 25 in jaw openings 26 and 27 which are adjacent the slots, a clockwise rotation of the screw separates the jaws and a counter-clockwise one draws them together. This involves a slight rotation of the trunnion nuts, so the fit of these must not be so tight that they will not move. Their outer cylindrical surfaces bear on the slot walls. Screw stem 21 projects outward from shank 12 at an angle of about 30°, thereby being very accessible, even to gloved hands. A knurled knob 28, separable from the stem, is provided on the outer end. It is necessary to separate the knob in order to assemble the tool.

The full lines of Fig. 1 show the wrench in its fully closed position. The dotted lines show the jaws open. While it is impossible to bring the jaws fully together in this type of wrench, it is seldom desirable to do so in aircraft servicing work. The jaws are always parallel and are always easily adjustable.

30 The invention claimed is:

1. An adjustable wrench comprising a fixed jaw, a shank integral therewith, a movable jaw, a collar associated therewith, said collar slidably fitting said shank, said shank being perforated by an inclined slot and the movable jaw being also perforated by a slot of similar incline so as to be registerable with the first, a trunnion nut mounted across each of said slots, and an adjusting screw threadedly mounted through both trunnion nuts, said screw having two oppositely threaded sections whereby said screw upon rotation partially rotates said trunnion nuts and moves the collar and associated jaw along the length of said shank.

45 2. An adjustable wrench comprising a fixed jaw, a shank integral therewith, a slidable jaw, a mounting for said jaw slidable on said shank and means for bringing said jaws together or moving them apart, said means comprising a trunnion nut mounted across a diagonal slot extending through the shank near the fixed jaw, a second trunnion nut mounted across a slanting slot registerable with the first slot and extending through the slidable jaw and a screw having two oppositely threaded portions rotatably mounted

through the said nuts and slots and projecting at approximately a 30° angle to the shank, whereby said slideable jaw may be adjusted along the length of said shank.

3. In combination in a wrench, a slotted, integral fixed jaw and shank member, a slotted movable jaw and collar fitting said shank member and trunnion-mounted screw means extending into the shank member slot and through the movable jaw piece to project at an acute angle to the shank, said screw means being oppositely threaded in its trunnion mountings to reversibly slide the movable jaw along the shank member upon selective rotation of said screw means.

THOMAS L. MAYRATH.
